UNITED STATES PATENT OFFICE.

TOLBERT J. ROBISON, OF CURWENSVILLE, PENNSYLVANIA.

HAND-STAMP.

No. 890,529.

Specification of Letters Patent.

Patented June 9, 1908.

Application filed October 23, 1907. Serial No. 398,742.

To all whom it may concern:

Be it known that I, TOLBERT J. ROBISON, a citizen of the United States, and a resident of Curwensville, in the county of Clearfield 5 and State of Pennsylvania, have invented a new and Improved Hand-Stamp, of which the following is a full, clear, and exact description.

The purpose of this invention is to provide 10 novel details of construction for a hand stamp, which adapt it for special service for stamping dates or other printed matter in books used by beneficial societies, wherein weekly accounts are kept, and that is also 15 available for general use as a dating stamp.

The invention consists in the novel construction and combinations of parts, as is hereinafter described and defined in the appended claims.

Reference is to be had to the accompanying drawings forming a part of this specification, in which similar characters of reference indicate corresponding parts in all the views.

Figure 1 is a partly sectional side view of 25 the hand stamp, seen in direction of the arrow *x* in Fig. 2, parts thereof being broken away; Fig. 2 is a vertical transverse sectional view, substantially on the line 2—2 in Fig. 1, and Fig. 3 is a perspective view, showing the 30 application of the improved stamp for marking a record in a book.

The body of the stamp comprises a handle piece 5, and a type holder 6. As shown, the handle piece 5 is preferably formed of plate 35 metal, having parallel sides and a suitable width and thickness, one edge thereof being concaved as at *a*, for a purpose that will hereinafter be explained. Upon the normally upper transverse edge of the part 5, a cylindrical grip piece 5^a is mounted and secured, preferably by insertion of said edge into a longitudinal groove *a'* formed in the grip piece, or the handle may be of other convenient form. The type holder 6 is in the form 40 of a plate metal box having parallel sides 6^a, and sloped ends 6^b, the space between the sides being so proportioned that the lower end of the handle piece 5 will fit neatly within the upper end of said holder box, wherein it is 45 secured by rivets *b*, or other means. The lower edges *c* of the side walls of the holder box 6 are convexed a suitable degree, and the upper edges thereof are correspondingly concaved, as shown in Figs. 2 and 3.

In one end of the type holding box 6, a wedge block 7 is slidably fitted, the smaller

end thereof being uppermost, and from said end extends an adjusting screw 7^a, that is passed upward through a perforation in the handle piece 5 at the end wherein the scalloped concavity *a* is formed, and upon the screw 7^a a thumb nut 7^b is mounted, that is seated upon the level portion on the handle piece produced by the scallop *a*.

In the holder box a plurality of dating 65 type 8 are placed, of a character to make a proper imprint upon a page in a book A, these type being assembled in the box, as indicated in Fig. 1. The type 8 may be of any preferred character taken from a font used 70 in commercial or other printing, and of course, have parallel sides and edges.

To compensate for the curvature given to the lower edge of the type holder box 6, and arrange the type 8 so as to have a printing 75 surface of the same convexity as is given to said lower edges, spacing blocks *d* are employed, which are wedge-shaped and when introduced between the type where they are needed, serve to take up gaps that would be 80 left between the type if this form of the spacing blocks was not given thereto.

It will be seen that if the wedge block 7 is slackened in adjustment at the time type 8 are introduced in the holder box, and blocks 85 *d* of proper thickness are placed between the printing type so as to neatly fill the holder box considered longitudinally, a proper adjustment of the nut 7^b on the adjusting screw 7^a will pull upward upon the wedge 90 block and cause it to bear upon the type, thus clamping them firmly within the holder.

To give lateral support to the hand stamp, a rocker arm 9 is provided, consisting of a metal rod bent into form, as indicated in the 95 drawings, said arm being shaped as follows: At an equal distance from the ends of the wire rod, two nearly right angular bends *e* are formed thereon, and the material *e'* between said bends, is given arcuate form, the 100 degree of curvature had by this portion of the rocker arm being similar to that given to the edges *c* of the holder box 6. The bends *e* produce upright limbs *g*, and at *h*, *h*, bends are formed that are equally distant from said 105 bends *e*, and the end portions *i*, *i*, that extend laterally from the bends *h* preferably are arched somewhat, as shown in Figs. 2 and 3. Their free end portions having threads thereon, are neatly fitted into lateral perforations in the walls 6^a near the end walls of the holder box 6, and are held therein by 110

thumb nuts *m*. The rocker arm 9, by its form and relative position, affords a lateral support for the type holder 6, the arcuate member *e'* of said arm that rests upon the 5 same base as the stamp in use, serving to hold said type box upright.

It will be seen that by grasping the grip piece 5^a, the convexed surface of the type in the box 6 may be rocked over an ordinary inking pad, and then applied upon a selected 10 page of a book A at a proper point for imprinting a date thereon, or any other matter set up in the holder box 6. Furthermore, the preferred use of the hand stamp for the 15 dating of attendance and dues paid by members of a benevolent association, is greatly facilitated by the specific construction of the device, as it enables the position of the stamp on a page of a ledger or similar book used by 20 the society, to be quickly and exactly determined by initially resting the member *e'* of the rocker arm alone upon the opened leaf of the book, then moving the stamp to the exact point on the leaf, then causing the type 25 to impinge upon the paper sheets and complete the operation by rocking the stamp; and it will be noted that the arched form given to the printing surface insures a perfect impression, as equal pressure may be given 30 to every portion of the type matter held in the box 6.

Having thus described my invention, I claim as new and desire to secure by Letters Patent:

35 1. A hand stamp, embodying a handle, a type holding box on one end of said handle and having its lower edge convexed, printing type having parallel sides, spacing blocks that are between the type and have wedge 40 form, and a wedge-shaped clamping block

adjustably held in the box at one end thereof, said block having a screw stem extended from the small end thereof, and a nut on said screw adapted for drawing on the block and clamping the type in the box. 45

2. A hand stamp, embodying a type holding box having convexed lower edges on its side walls, a handle on the upper portion thereof, means for securing type in the box so that their printing faces assume arched 50 form, and a rocker arm projected laterally and downwardly from the side of the box and spaced therefrom, the lower edge of said arm being convexed similarly to the arched face of the type in the holder box, whereby the 55 arm affords lateral rockable support to the stamp when used.

3. A hand stamp, comprising a type holding box, a handle thereon, said box having curved lower edges on its side walls and upwardly converged end walls, type having parallel sides and fitted into the box, wedge-shaped spacing blocks inserted between the type for giving the working face of the assembled type arched form, a wedge block in the 60 box at one end thereof and having a screw on one end, means for drawing on the screw so as to press the wedge block against the type, and a rocking arm projected at one side of the type holding box, said arm having an 65 arched member that rests on the paper when the type surface is rocked for printing matter thereon.

In testimony whereof I have signed my name to this specification in the presence of 75 two subscribing witnesses.

TOLBERT J. ROBISON.
